(57) **CLAIM**

The ornamental design for a sports glove wrap, as shown and described.

DESCRIPTION

FIG. 1 is a perspective view illustrating the back of a baseball fielders glove and including the present invention as attached thereto.

FIG. 2 is a perspective view of the device in an unfastened state.

FIG. 3 is a perspective view of the device in a fastened state.

FIG. 4 is a top plan view of the device.

FIG. 5 is a bottom plan view of the device.

FIG. 6 is a left side elevational view of the device.

FIG. 7 is a right side elevational view of the device.

FIG. 8 is a front elevational view of the device; and,

FIG. 9 is a rear elevational view of the device.
